(57) **CLAIM**

An ornamental design for a wheel, as shown and described.

DESCRIPTION

FIG. 1 is a rear perspective view of an embodiment of a wheel showing our new design;

FIG. 2 is a front perspective view thereof;

FIG. 3 is a rear elevational view thereof;

FIG. 4 is a top plan view thereof; the bottom plan view being identical to FIG. 4;

FIG. 5 is a right side elevational view thereof, the left side elevational view being identical to FIG. 5;

FIG. 6 is a front elevational view thereof; and,

FIG. 7 is a side cross-sectional view thereof, for clarity of disclosure, taken at Line 7-7 shown in FIG. 3.

The broken lines shown illustrate portions of the wheel that form no part of the claimed design.
